UNITED STATES PATENT OFFICE.

PHILIP CARPELES, OF MILWAUKEE, WISCONSIN.

DESIGN FOR A TRUNK.

SPECIFICATION forming part of Design No. 18,875, dated January 22, 1889.

Application filed December 21, 1888. Serial No. 294,331. Term of patent 7 years.

To all whom it may concern:

Be it known that I, PHILIP CARPELES, a citizen of the United States, residing at Milwaukee, in the county of Milwaukee and State 5 of Wisconsin, have invented and produced a new and original Design for a Trunk; and I do declare the following to be a full, clear, and exact description of the same, reference being had to the accompanying drawing, forming 10 a part thereof.

The said drawing is a perspective view of a trunk showing my design, which consists in both configuration and surface ornamentation.

15 The shape of the trunk is that of an oblong body rounded at its upper and lower front and rear edges, and having raised portions *a a* entirely surrounding each end, and other raised curved portions, *b b b*, on the top of the 20 trunk intermediate between the said raised end portions, *a a*, and central vertical raised portions, *c c*, on the trunk ends, vertical raised portions *d d d* on the sides of the trunk, (the front side only being shown in the drawing, 25 but the design of the rear side being exactly the same,) horizontal raised portions *e e'* at the sides and ends of the base of the trunk-top, and lower raised portions, *f*, on the sides of the trunk. The surface of the raised 30 portions *b d f* is thus ornamented—viz., by leaf-shaped figures *g g*, each showing against a dark triangular background, *h*, on the raised portions *b b* above the raised portion *e*, inverted-leaf-shaped figures *i i*, each showing 35 against a dark inverted triangular background, *j*, beneath the said raised portion *e*; and longer leaf-shaped figures, *k k*, each showing against an oblong dark background, *m*, at

the points of junction of the raised portions *d d* and *f*. The upper corners of the raised 40 portions *a a* are ornamented by smooth-surfaced designs *n n*, of irregular angular shape. These features comprise the essential and striking elements of my design as a whole, and those which give a distinctive and peculiар appearance to my said trunk, and, 45 while the arrangement of the other and minor features shown in my drawing are of my own design and arrangement, those hereinbefore especially named are the ones deemed by me 50 important.

What I claim is—

The design for a trunk herein shown and described, consisting of an oblong form rounded at its upper and lower front and rear edges 55 and having raised portions entirely surrounding each end, other raised curved portions on the top of the trunk intermediate between said raised end portions, central vertical raised portions on said ends, horizontal raised 60 portions at the sides and ends of the base of the trunk-top, lower raised portions on the sides, and vertical raised portions on the sides between the said horizontal raised portions, the said raised portions on the sides being 65 ornamented by leaf-shaped figures, each showing against a dark background, and smooth-surfaced ornaments of irregular angular shape at the upper corners of the raised end portions, as set forth.

In testimony whereof I affix my signature in presence of two witnesses.

PHILIP CARPELES.
